ABSTRACT: A method and apparatus for making guide bracket and ball bearing carrier units from a plurality of channel-shaped carrier members with ball bearing sockets, ball bearings, and a longitudinally moving channel-shaped guide bracket strip comprising a plurality of guide bracket sections defined by longitudinally spaced notched portions. The carrier members are sequentially fed to a working position in an assembling station in timed relation to the operative forward movement of the strip, each operatively positioned carrier member being held against movement while in said working position, the guide bracket strip uninterruptedly moving through said assembling station while ball bearings are being fed to positions between the sockets in the carrier member legs and the flanking legs of the moving guide bracket strip, thereby effecting a rollable interengagement of the carrier member and the adjacent coacting guide bracket section. The carrier member is then released from its said assembling position, and the interengaged members are moved forwardly to cutting apparatus at which successive completed units are operatively severed.

**METHOD AND APPARATUS FOR MAKING GUIDE
BRACKET AND BALL-BEARING CARRIER UNITS FOR
DRAWERS AND THE LIKE**

BACKGROUND OF THE INVENTION

1. The Field of the Invention

This invention relates to a method and apparatus for making guide bracket and ball bearing carrier units, particularly for inserting a channel-shaped ball bearing carrier member into a channel-shaped guide racket for drawers and the like.

2. The Known Art

Guide brackets of the above-referred-to category contain laterally opposite ball bearing tracks which are generally pressed outwardly from their opposite lateral legs in the form of longitudinal grooves for receiving and rollably supporting pairs of laterally opposite ball bearings interengaged with a carrier member rollably movable within the guide bracket—the said carrier member being adapted to rollably receive therein a drawer slide member, all in well-known manner. It has heretofore been the practice to assemble the guide bracket, carrier member and ball bearings by inserting the carrier member and ball bearings into the bracket from one end thereof—an assembling operation performed after the completion of all the forming and cutting operations on said bracket. This has proven to be a costly procedure, first because it involves considerable manual labor, and second because it involves a time-loss factor since such assembling operation could not be performed during a continuous operative movement of the uncut guide bracket strip along the operative forming and cutting path, but rather after fully formed sections of the guide bracket have been cut from said strip.

3. Objectives of the Invention

It is one of the objectives of this invention to perform the inserting operation of the carrier member and ball bearings during the operative movement of the uncut length of guide bracket strip along the forming path, without interrupting the continuity of such movement. A secondary objective is to enable successive sections of the guide bracket strip into which carrier members and ball bearings have been inserted by the method of this invention to be separated into finally completed units without interfering with the continuity of the said forming and assembling operations.

Other objects, features and advantages will appear from the drawings and the description hereinafter given.

SUMMARY OF THE INVENTION

The method and apparatus of this invention effect the successive assembly of carrier members and sets of ball bearings with sections of a continuously moving guide bracket strip, the carrier members and ball bearings being fed to an assembling position in non noninterfering relation to the operative path of said strip.

Among the operations performed on the longitudinally moving channel-shaped strip of metal out of which a plurality of guide brackets are to be formed are the steps of forming notches in the laterally opposite legs of the strip, thereby separating successive portions of the strip into guide bracket sections of predetermined equal lengths, the notched portions also performing certain operative steps. As the strip moves along its operative path the forward portion thereof passes through an assembling station defined by two laterally opposite walls supporting therebetween a housing the base of which comprises two rails positioned for underlying supporting engagement with the base of a carrier member fed into the housing by suitable means, said carrier member having in each upright leg two longitudinally spaced open ball bearing sockets. The forward section of the channel-shaped guide bracket strip is so positioned within the housing that the base is spaced below the said rails and the legs flank the legs of said carrier member, the grooved tracks of the guide bracket being at the level of said sockets.

There are two ball bearing feed pipes or chutes that extend through each of said laterally opposite walls with discharge outlets at the level of said ball bearing sockets of the carrier member resting on said rails. The longitudinal distance between said outlets is equal to the longitudinal distance between said sockets, the front or leading ball at each outlet being engageable with the outwardly protruding grooved track of the adjacent guide bracket leg. The arrangement is such that the balls in said respective feed pipes are maintained in line while the guide bracket is moving forwardly. In the preferred construction each feed pipe is provided with an air jet for maintaining the leading ball in operative engagement with the adjacent coacting socket during the assembling operation.

As a guide bracket section enters the said housing during the operative movement of the strip, the leading notched portions will reach a position coinciding with the laterally opposite ball bearing discharge outlets. The leading ball at each outlet will pass through the corresponding notch and settle in the adjacent coacting socket. As the strip continues its forward movement the laterally opposite rear edges of said notched portions (the leading edges of the following guide bracket section) will engage the respective leading and next adjacent balls at their points of contact, separating them—the continued movement of the strip forcing the next adjacent balls back, whereby they come into rolling engagement with the outer surfaces of the grooved tracks of the respective guide bracket legs, the leading balls now being rollably positioned between the respective sockets and the adjacent grooved tracks. This is the first step in the assembly of the carrier member, ball bearings and guide racket. As the strip moves on and the said notched portions reach the second set of oppositely disposed discharge outlets, the above-described assembly process is repeated, whereby four ball bearings are now rollably positioned between the grooved tracks and sockets of the guide bracket section and the carrier member, said section and member being now rollably interengaged.

This assembling action takes place while the guide bracket strip is continuously moving forwardly along its operative path; but the carrier member is, during such action, maintained stationary by the gate in engagement with the front edge of the carrier member while the said strip is moving forwardly therebeneath. After the completion of the assembling operation, the said gate is removed from its obstructing position, at which time the carrier member is pushed forwardly to a cutting station where suitable cutting dies, moving with the strip in known manner, sever the foremost assembled section from the rest of the strip.

In the form illustrated the gate is spring-loaded and the carrier member engaged and pushed forwardly by the rear upstanding stop in the strip section being assembled; but other forms of gates, such as known suitably timed electromechanically operated gates, may be employed within the scope of this invention. The carrier members are sequentially fed on to the rails at the assembling station, the particular illustrated embodiment comprising a vertically stacked arrangement of carrier members gravitationally fed; but inclined slides with known suitably timed feeding means may be employed for coaction with the operative movement of the guide bracket strip within the scope and intent of this invention.

DESCRIPTION OF THE DRAWINGS

FIG. 1 is a fragmentary plan view of a portion of the flat steel stock to be formed into a channel-shaped guide bracket strip for use in this invention, the piece being shown after the notching operations but before the required forming and piercing operations.

FIG. 2 is a section of FIG. 1 taken along line 2—2.

FIG. 3 is a fragmentary plan view of the formed and pierced channel-shaped guide bracket strip ready for employment in the method and apparatus of this invention.

FIG. 4 is a side view of FIG. 3, a fragment being broken away for clarity.

FIG. 5 is a section of FIG. 4 taken along line 5—5.

FIG. 6 is a side elevation of the carrier member of this invention.

FIG. 7 is a section of FIG. 6 taken along line 7—7.

FIG. 8 is an enlarged section of FIG. 6 taken along line 8—8.

FIG. 9 is a perspective view of a completed assembly of the slide bracket section and ball bearing carrier made by the method and apparatus of this invention, a portion being broken away for clarity.

FIG. 10 is a perspective view, with parts broken away for clarity, of portions of the apparatus of this invention, showing a fragmentary portion of the slide bracket strip being fed into the apparatus and showing a stacked arrangement of carrier members within the housing of the apparatus.

FIG. 11 is a vertical section of the apparatus of FIG. 10 taken substantially along line 11—11 thereof and along the line 11—11 of FIG. 12.

FIG. 12 is a fragmentary section of FIG. 11 taken along line 12—12 thereof.

FIG. 13 is a fragmentary section of FIG. 11 taken along line 13—13 thereof, the gate being shown in a closed position, the carrier members being omitted.

FIG. 14 is a fragmentary section of FIG. 13 taken along line 14—14 thereof.

FIG. 15 is a side elevation of the apparatus with a part broken away showing the position of a notch of the guide bracket section approaching the first ball discharge outlets.

FIG. 16 is a section of FIG. 15 taken along line 16—16.

FIG. 17 is a fragmentary section taken substantially along line 12—12 of FIG. 11 showing the notch in a position coinciding with the first ball discharge outlets.

FIG. 18 is a section of FIG. 17 taken along line 18—18.

FIG. 19 is a section of FIG. 17 taken along line 19—19 thereof.

FIG. 20 is a section like that of FIG. 17 but showing the rear edge of the slot in a position just beyond the point of contact between the leading ball and the next adjacent ball, the legs of the guide bracket section now separating said leading ball and said next adjacent ball.

FIG. 21 is a section of FIG. 20 taken along line 21—21 thereof.

FIG. 22 is another section like that of FIG. 17, but showing the said notch in an operative position at the second or forward ball discharge outlets.

FIG. 23 is a section of FIG. 22 taken along line 23—23.

FIG. 24 is a fragmentary section substantially like FIG. 13, but showing the carrier members operatively in place and showing the gate in an open position with the assembled parts moving outwardly therebeyond.

FIG. 25 is a schematic side elevation, partly in section, showing the assembling station, a guide bracket strip passing therethrough to and through a severing station.

DESCRIPTION OF PREFERRED EMBODIMENT

In carrying out the method of this invention a length of flat steel stock 23 is first notched at spaced laterally opposite portions 24 (FIGS. 1 and 2) and then formed into a substantially channel-shaped configuration with pressed-out longitudinal grooved tracks, fastener apertures and stops as shown in FIGS. 3, 4 and 5, in accordance with known cutting and forming procedures, resulting in the formation of the guide bracket strip 25. As illustrated, this strip is divided into a plurality of sections 25a, 25b etc. separated by notched portions, generally designated 26, extending downwardly to the base 27. The strip comprises the two upstanding legs 28 and 29 the upper portions of which are pressed outwardly to form the longitudinal grooved tracks 30 and 31, the upstanding stops 32 and the fastener apertures 35, 36, 37, 38 and 39, the upstanding stop 33 being formed after the assembling operation hereinafter described.

The carrier member 41 (FIGS. 6, 7 and 8) which is to be assembled within the guide bracket 25 is also of channel-shaped

configuration, having a raised base 42 and two upstanding legs 43 and 44, each of said legs having open sockets for operatively accommodating ball bearings, leg 43 having the sockets 45 and 46 and leg 44 having the sockets 47 and 48, the sockets on each leg being in longitudinally spaced relation and at the same horizontal level. FIG. 9 illustrates the finished assembly of a section of the guide bracket strip 25 and the carrier member 41 with a pair of rear ball bearings 49a and 50a and a pair of front ball bearings 51a and 52a operatively in place.

FIG. 25 semischematically illustrates the operative path of the guide bracket strip 25, it being shown moving forwardly upon a supporting floor 53 through the assembling station generally designated 54, and forwardly therefrom to the final severing apparatus generally designated 55. On opposite sides of the structure constituting said station 54 are ball bearing feed pipes extending downwardly from the bins 55 and 56, feed pipes 57 and 58 extending down from bin 55 and feed pipes 59 and 60 extending down at the laterally opposite side from the bin 56. At the base of said feed pipes are air pressure ducts generally designated 61 the operation of which will be hereinafter described. In the particular embodiment illustrated, carrier members 41 are fed from an upper position downwardly to a working position in operative relation to the path of said guide bracket strip 25 for operative assembly with two pairs of ball bearings in the manner hereinbelow set forth.

The illustrated structure of the assembly station 54 comprises two laterally opposite walls 62 and 63 flanking the lower portion of a housing 64 comprising the laterally opposite sidewalls 65 and 66, the front wall 67, the rear wall 68 and the two parallel rails 69 and 70 at the base of the housing. In the construction shown the angle bars 71 and 72 secured to the tops of the respective said walls 63 and 62 are attached to the outer surfaces of the said respective walls 66 and 65 of said housing. The base of the said rear wall 68 contains a recessed portion 73 to permit the operative passage therethrough of the upstanding stops 32 of the guide bracket strip 25 during its operative movement forwardly. The said front wall 67 contains a recess 74 defined at the rear by the wall 75, there being a gate 77 pivotally mounted on said front wall 67 at 78 and urged rearwardly into its closed position by the leaf spring 79 mounted on said front wall 67 as shown. The bottom portion 80 of said gate 77 extends, when in its operatively closed position, as shown in FIGS. 11 and 13, between said rails 69 and 70 and therefore in obstructing relation to the longitudinal path of the carrier member as defined by said rails. When said gate 77 is in its operatively retracted position as shown in FIG. 24, the passageway 81 between and above said rails is unobstructed by said gate, thereby to permit the forward passage therebeyond of the interengaged guide bracket and carrier member, as will more clearly hereinafter appear.

The said ball bearing feed pipes 57, 58, 59 and 60 extend through the lower portions of the corresponding ones of said walls 62 and 63 to their respective ball discharge outlets 57a, 58a, 59a and 60a, said outlets being at the level of said grooved tracks 30 and 31 of said guide bracket strip 25, the longitudinal distance between the discharge outlets on each side being equal to the longitudinal distance between the said sockets on each leg of the carrier members. Disposed at the same level as said grooved tracks 30 and 31 and said respective outlets 57a, 58a, 59a and 60a are the laterally opposite longitudinal slotted portions 82 and 83 of said sidewalls 66 and 65 of the said housing 64, the opposite ends of each of said slotted portions having enlarged portions 84 proportioned to receive therethrough the ball bearings. Operatively connected to each of said feed pipes is an air pressure duct 61 connected to a suitable source of air supply.

In the operation of this method and apparatus, carrier members 41 are inserted through the top opening 85 of the housing 64 in stacked arrangement, the lowermost of said carrier members resting upon said rails 69 and 70. The said floor 53 slidably supporting the said guide bracket strip 25 is so positioned that the base 27 of said strip is disposed in spaced relation below the said rails 69 and 70, and the said legs 28 and 29

are in flanking relation to the legs 44 and 43 of said carrier member, as clearly shown in FIGS. 11 and 19. The distance between the said sidewalls 65 and 66 is sufficient to accommodate therebetween said carrier members, but less than the width of said guide bracket strip to permit the legs of said strip to flank said sidewalls and an operatively positioned carrier member.

The ball bearings are in linear formation within the respective feed pipes (see FIG. 19), the front or leading ball in each of said feed pipes being positioned for engagement with the correspondingly positioned carrier member socket. More specifically, the leading ball 49a is engageable with the socket 47, the leading ball 50a is engageable with the socket 45, the leading ball 51a is in engagement with the socket 48 and the leading ball 52a is in engagement with the socket 46. The grooved tracks 30 and 31 are so positioned as to be in line with the points of contact of the respective leading and next adjacent balls. Hence, each of said grooved tracks is adapted to form a separating wall between the leading balls on its side and the next adjacent balls, thereby to effect an operative assembly of the carrier member and guide bracket section as will more clearly appear from the following description.

As the guide bracket strip 25 moves forwardly in the direction of arrow A, the notched portions 26a and 26b will reach a position at which they coincide with the respective discharge outlets 57a and 59a, the leading balls 50a and 49a gravitationally passing downwardly through said respective notched portions into engagement with the respective sockets 45 and 47 of the carrier member, the air jets from the respective ducts 61 helping to hold the said leading balls in engagement with said sockets. During this action the other balls in the respective feed pipes 57 and 59 move down to correspondingly lowered positions, and remain there until said rear edges 86a and 86b of the said respective notched portions 26a and 26b come operatively into engagement with the respective contacting leading and next adjacent balls 50a, 50b and 49a, 49b. Since, as aforesaid, said grooved tracks 30 and 31 are at the same levels as said respective discharge outlets 59a and 57a and said sockets 45 and 47, and are in substantial longitudinal alignment with the respective points of contact of said leading and next adjacent balls, the continued forward movement of said bracket strip 25 will bring said upper track portions of said edges 86a and 86b between the respective two front balls at each of said outlets 57a and 59a, thereby separating them. Thus the said leading ball 50a will now be positioned between the socket 45 of the carrier member and the inner concave surface of the grooved track 31, and the leading ball 49a will be positioned between the socket 47 and the inner concave surface of the grooved track 30. In the above-mentioned separating action of the two front balls at each outlet, the line of balls behind the respective leading balls will be pushed back a distance equal to the thickness of the walls of the respective grooved tracks 31 and 30, balls 50b and 49b now being the new leading balls positioned for operative assembly with the next oncoming guide bracket section and a newly delivered carrier member.

The first part of the assembly has now been effected, balls 49a and 50a being in properly assembled positions between their respective grooved tracks 30 and 31 and the corresponding sockets of said carrier member 41. As the guide bracket strip continues its forward movement, the said notched portions 26a and 26b will reach a position at which they coincide with discharge outlets 58a and 60a, the leading balls 52a and 51a passing through said notched portions, settling into sockets 46 and 48 and, upon the further continued movement of the strip forwardly, becoming rollably positioned between said last-mentioned sockets and the adjacent grooved tracks 31 and 30, the new leading balls at said outlets 58a and 60a now being the balls 52b and 51b. The assembly has thus been completed.

During the aforesaid assembling operation the front edge 41a of the carrier member 41 was in engagement with the lower portion 80 of the said spring-loaded gate 77, the gate

thereby preventing any forward movement of the carrier member while the slide member was continuing its forward movement beyond the gate, this being possible due to the fact that the said guide bracket strip is moving along a clear path not obstructed by said gate. When, during the forward operative movement of the guide bracket strip, its stop element 32 comes into engagement with the rear edge 41b of the carrier member 41, said member will be propelled thereby forwardly against the yieldable resistance of the gate 77, whereby the gate will be forced into its open position illustrated in FIG. 24, thereby permitting the carrier member to move forwardly with the connected section of the guide bracket strip towards the severing apparatus 55.

Said severing apparatus, of conventional construction, consists of a body portion 87 adapted to operably move with and at the same speed as that of the guide bracket strip 25 at predetermined times. The strip, during its forward movement, enters the apertured portion 88 of said severing apparatus 55 whereupon the severing tool 89 is operatively tripped and caused to move downwardly in known manner to sever the connecting strip 90 constituting the base of the notch which separated the foremost section 25d from the following section of the strip. The severed section 25d now a completed and finally assembled unit like that shown in FIG. 9.

In the above description, the invention has been disclosed merely by way of example and in preferred manner, but obviously many variations and modifications may be made therein. It is to be understood, therefore, that the invention is not limited to any particular form or manner of practicing same.

We claim:

1. In a method of making guide bracket and ball bearing carrier units, the steps of providing a channel-shaped guide bracket section and a channel-shaped carrier member transversely narrower than said guide bracket section and having ball bearing sockets in the legs thereof, moving said guide bracket section forwardly along a predetermined operative path towards and through an assembling station, the legs of said section extending upwardly from the base thereof, delivering said carrier member at said station to an assembling position at which the base of the carrier member is above the base of said guide bracket section and the legs of said carrier member are spaced inwardly from the legs of said guide bracket section to provide a ball bearing space between each of said sockets and the respective inner surfaces of the legs of said guide bracket section during the operative movement thereof within said station, holding said carrier member in said position, feeding a ball bearing to each of said sockets and holding them in place, whereby upon said operative movement of said guide bracket section within said station the said inner surfaces of the legs of the guide bracket section rollably engage said respective ball bearings and hold them in said ball bearing spaces in operative engagement with said respective sockets, thereby to rollably interengage said guide bracket section and said ball bearing carrier member, releasing said carrier member from said assembling position and moving said interengaged carrier member and guide bracket section forwardly.

2. In a method of making guide bracket and ball bearing carrier units, the steps according to claim 1, said step of delivering the carrier member being performed from a position in noninterfering relation to the said operative path of said guide bracket section.

3. In a method of making guide bracket and ball bearing carrier units, the steps according to claim 2, said operative movement of the guide bracket section being continuous along said path, through said assembling station and therebeyond, whereby the said operative movement of said section remains uninterrupted during the said step of holding said carrier member in said assembling position.

4. In a method of making guide bracket and ball bearing carrier units, the steps according to claim 3, said step of feeding said ball bearing being performed gravitationally from a position above and in noninterfering relation to the said operative path of said guide bracket section.

5. In a method of making guide bracket and ball bearing carrier units, the steps according to claim 1, said step of holding said operatively fed ball bearings in place at said respective sockets being performed by directing air jets at said ball bearings.

6. In a method of making guide bracket and ball bearing carrier units, the steps according to claim 1, said step of moving said interengaged carrier member forwardly being performed by engaging a portion of the forwardly moving guide bracket section with said carrier member.

7. In a method of making guide bracket and ball bearing carrier units, the steps of providing a channel-shaped guide bracket strip and a plurality of channel-shaped carrier members each transversely narrower than said guide bracket strip and having laterally opposite ball bearing sockets in the legs thereof, said strip comprising a plurality of guide bracket sections separated by pairs of laterally opposite notched portions in the legs of the strip, moving said strip forwardly along a predetermined operative path towards and through an assembling station, the legs of said strip extending upwardly from the base thereof, sequentially feeding said carrier members, in predetermined timed relation with respect to the movement of said strip, to an assembling position within said station at which the base of the carrier member is disposed above the operative path of the base of said strip and the legs of said carrier member are spaced inwardly from the path of the corresponding legs of said channel-shaped strip to provide a ball bearing space between each of said sockets and the respective inner surfaces of the legs of a guide bracket section operatively positioned at said assembling station, holding said carrier member at said assembling position, feeding ball bearings to said respective laterally opposite sockets through a pair of said laterally opposite notched portions of a section of said guide bracket strip operatively within said assembling station, whereby upon the continued operative forward movement of said strip the rear edges of said last-mentioned notched portions engage the outer portions of said ball bearings and the inner surfaces of the legs of the following guide bracket section rollably engage said respective ball bearings and hold them in said ball bearing spaces in operative engagement with said respective sockets, thereby to rollably interengage said guide bracket section and said ball bearing carrier member, releasing said carrier member from said assembling position and moving said interengaged carrier member and guide bracket section forwardly.

8. In a method of making guide bracket and ball bearing carrier units, the steps according to claim 7, said feeding of ball bearings being performed by arranging laterally opposite linear formations of ball bearings for gravitational downward movement towards the operative positions of the leading ball bearings, said leading ball bearings being positioned for operative engagement with said respective sockets, whereby the said rear edges of said laterally opposite notched portions will, upon operative engagement with the said outer portions of said leading ball bearings, simultaneously engage the respective next adjacent ball bearings of said linear formations to separate said latter ball bearings from said leading ball bearings, whereby said respective next adjacent ball bearings will rollably engage the respective outer surfaces of said respective legs of the adjacent guide bracket section and will become the leading ball bearings for operative movement through the oncoming notched portions of said strip.

9. In a method of making bracket and ball bearing carrier

units, the steps according to claim 8, said carrier members having at laterally opposite portions two spaced horizontally aligned sockets on the legs thereof, said legs of said guide bracket sections having at the upper portions thereof longitudinal grooved tracks at the same level as said horizontally aligned sockets, said linear formations of ball bearings comprising two-spaced pairs of laterally opposite formations, the leading ball bearings of said formations being operatively adjacent and at the same level as the corresponding sockets of 10 said carrier member, whereby the feeding steps of said ball bearings will occur through each pair of laterally opposite notched portions successively at the laterally opposite sockets of said carrier member.

10. In a method of making guide bracket and ball bearing carrier units, the steps according to claim 7, said operative movement of the guide bracket strip being continuous along said path, through said assembling station and therebeyond, whereby the said operative movement of said section remains uninterrupted during the said step of holding said carrier member in said assembling position, the movement of said interconnected carrier member and guide bracket strip continuing to a severing station, and the further step of severing the foremost section from the next adjacent section at the notched portions therebetween.

11. An apparatus for making guide bracket and ball bearing carrier units from a plurality of carrier members with ball bearing sockets, ball bearings and a longitudinally movable channel-shaped guide bracket strip having a plurality of longitudinally aligned guide bracket sections, comprising an assembly housing having at the base thereof two spaced longitudinal rails proportioned to support thereon one of said carrier members, carrier member feeding means communicating with said rails, retractable holding means positioned and proportioned for releasable holding engagement with a carrier member operatively positioned on said rails, longitudinal supporting means for said moving guide bracket strip spaced below said rails and said holding means, and ball bearing feeding means for laterally opposite linear formations of ball bearings, said feeding means having discharge outlets above 40 said rails.

12. An apparatus according to claim 11, said holding means comprising a retractable gate at the forward portion of said housing.

13. An apparatus according to claim 11, each of said ball-feeding means having a feed pipe extending from a predetermined level above said rails down to a discharge outlet in the region of said rails.

14. An apparatus according to claim 11, said housing having laterally opposite walls spaced apart a distance sufficient for 50 operatively accommodating therebetween one of said carrier members operatively positioned on said rails, said distance being less than the transverse width of said channel-shaped guide bracket strip, whereby the legs of said strip will be adapted to operatively move in flanking relation to said walls, said laterally opposite walls having apertured portions substantially at the level of said ball bearing discharge outlets.

15. An apparatus according to claim 14, said ball bearing feeding means having a plurality of feed pipes extending from a predetermined level above said rails down to corresponding discharge outlets in the regions of said rails, and air jet ducts communicating with the bottom portions of said respective pipes for directing air towards said discharge outlets.
